(57) CLAIM

We claim the ornamental design for an overhead vacuum console, as shown and described.

DESCRIPTION

FIG. 1 is a perspective view of an overhead vacuum console showing our new design;

FIG. 2 is a rear elevational thereof;

FIG. 3 is a bottom plan view thereof;

FIG. 4 is a right side elevational view thereof;

FIG. 5 is left side elevational view thereof; and,

FIG. 6 is a perspective view with a hose being extended. The top of the overhead vacuum console forms no part of the claimed design.

The broken lines are for illustrative purposes only and form no part of the claimed design.
